FIG. 1 is a top plan view illustrating a tackless carpet stripping showing our new design;

FIG. 2 is a rear elevational view thereof;

FIG. 3 is a front elevational view thereof;

FIG. 4 is a bottom elevational view thereof;

FIG. 5 is a left-side elevational view thereof;

FIG. 6 is a right-side elevational view thereof;

FIG. 7 is a top plan view illustrating a second embodiment of a tackless carpet stripping showing our new design;

FIG. 8 is a rear elevational view of the tackless carpet stripping illustrated in FIG. 7;

FIG. 9 is a front elevational view of the tackless carpet stripping illustrated in FIG. 7;

FIG. 10 is a bottom elevational view of the tackless carpet stripping illustrated in FIG. 7;

FIG. 11 is a left-side elevational view of the tackless carpet stripping illustrated in FIG. 7; and

FIG. 12 is a right-side elevational view of the tackless carpet stripping illustrated in FIG. 7.

We claim:

The ornamental design for a tackless carpet stripping, as shown and described.
